(57) **CLAIM**

The ornamental design for an inverter, as shown and described.

DESCRIPTION

FIG. 1 is a front perspective view of an inverter showing my new design;

FIG. 2 is an elevated front view thereof;

FIG. 3 is an elevated rear view thereof;

FIG. 4 is a top plan view thereof;

FIG. 5 is a bottom plan view thereof;

FIG. 6 is left side view thereof; and,

FIG. 7 is a right side view thereof.

The broken lines in the figures merely illustrate the environment for the inverter of the present design and therefore form no part of the claimed design.
